CLAIM

The ornamental design for a comminuted cheese blend product, as shown and described.

DESCRIPTION

FIG. 1 is a top perspective view of the comminuted cheese blend product in accordance with a first embodiment of this invention, of relatively light colored cheese shreds and relatively dark colored cheese cubes; and,

FIG. 2 is a top perspective view of the comminuted cheese blend product in accordance with a second embodiment of this invention, of relatively darker colored cheese shreds and relatively lighter colored cheese cubes.

The top perspective view from the side opposite the side shown in FIGS. 1 and 2 are substantially mirror images thereof.
